DESIGN FOR A MANICURIST KIT

Eleanor Conradsen, Hollywood, Calif.

Application January 17, 1938, Serial No. 74,335

Term of patent 14 years

To all whom it may concern:

Be it known that I, Eleanor Conradsen, a citizen of the United States and a resident of the city of Hollywood, county of Los Angeles, State of California, have invented a new, original, and ornamental Design for a Manicurist Kit, of which the following is a specification, reference being had to the accompanying drawings forming a part thereof.

I claim:

The ornamental design for a manicurist kit, as shown,

ELEANOR CONRADSEN,
